UNITED STATES PATENT OFFICE.

JOHN E. PARAMORE, OF WAUSAU, WISCONSIN, ASSIGNOR, BY DIRECT AND MESNE ASSIGNMENTS, OF ONE-HALF TO JOHN J. MURRAY AND JOHN CAMERON, BOTH OF SAME PLACE.

MINING PAN OR SETTLER.

SPECIFICATION forming part of Letters Patent No. 357,852, dated February 15, 1887.

Application filed December 2, 1885. Serial No. 184,429. (No model.)

To all whom it may concern:

Be it known that I, JOHN E. PARAMORE, of Wausau, in the county of Marathon, and in the State of Wisconsin, have invented certain new and useful Improvements in Mining Pans or Settlers; and I do hereby declare that the following is a full, clear, and exact description thereof.

My invention relates to machines for separating metal from quartz or other substances; and it consists in certain peculiarities of construction, as will be hereinafter described with reference to the accompanying drawings and subsequently claimed.

While I herein show crushing and screening mechanism and describe it in detail, I do not consider such mechanism as a part of this invention, and do not claim it herein, it being only described and illustrated as the preferred means to be used for preparing material for treatment in my improved mining pan or settler, and which mechanism forms the subject of a separate application, No. 209,467, filed July 29, 1886.

Figure 1 of the drawings represents a sectional elevation of my improved mining pan or settler and a side elevation of the crushing and screening mechanism used in connection therewith; Fig. 2, an end elevation of the crushing and screening mechanism; and Fig. 3 a perspective view of one of the sieves.

A A represent vertical standards, suitably braced apart to form the main frame of a crushing-mill, said standards being provided with bearings for the shafts B B' of a series of horizontal crushing-rolls, C, vertically arranged in pairs. The vertical standards A A are also provided with brackets b, having journals c for gear-wheels D, the latter meshing with gear-wheels E, journaled to the shafts B of the crushing-rolls C. These gear-wheels E in turn mesh with gear-wheels E', journaled to the shafts B' of the inner crushing-rolls, and by this arrangement of gearing the several crushing-rolls are made to turn toward each other.

The crushing-rolls C may be either smooth or corrugated upon their surfaces; or the upper pair of rollers may be corrugated and the lower pairs smooth, this construction being shown by Fig. 1.

The standards A A are slotted, as at a, Fig. 2, for the reception of the springs a' and the bearing-boxes a', against which said springs impinge, and wherein the upper roller-shafts, B B', are mounted. All of the roller-shafts 55 may be mounted in the same way, if found desirable. This construction serves to retain the rollers C in their normal position, but at the same time allows a yielding motion should any substance of more than ordinary size or 60 hardness be fed thereto from the hopper.

The shaft B of one lower crushing-roll is extended to form a main shaft, F, an additional bearing, d, for the same being provided at the top of a vertical post, G. This main shaft F 65 has keyed thereto a beveled gear-wheel, H, designed to mesh with a similar wheel, I, keyed to a vertical shaft, K, having its bearings in brackets e, secured to the vertical post G, a bracket, f, projecting from one of the frame-standards, and a socket, g, on the base-piece M. The upper end of the vertical shaft K is provided with an eccentric, h, having a rod-connection, i, with a hopper, N, loosely hung by links k to the main frame, so as to have a 70 vibratory motion when said eccentric is operated. Hung by links m to the main frame, a suitable distance below the crushing rolls, are a series of horizontal sieves, O, united at their ends by vertical strips n, one of said strips being connected to the rod o of an eccentric, p, secured to the vertical shaft K. By this eccentric connection a vibratory motion is imparted to the sieves when the vertical shaft is 75 revolved.

Suitably suspended in the main frame below the sieves is a trough, P, leading to the hopper r of a pan, R, having a vertical central shaft, S, bearing in a socket, s, on the base-piece M, and a bracket, t, projecting from one 80 of the vertical frame-standards. This shaft S is hollow above the bottom of the pan, the lower end of this hollow portion being provided with a series of perforations, as shown at u, and a water-supply pipe, T, is introduced 85 and extended any suitable distance down the bore of said shaft.

To the lower or solid portion of the shaft S, below the pan, is secured a beveled gear-wheel, U, meshing with a similar wheel, V, on one 90

end of a shaft, W, which revolves in bearings v on the base-piece M. This shaft W at its other end carries a beveled gear-wheel, X, which meshes with a similar wheel, Y, on the vertical shaft K, motion being imparted to the various operating parts of the machine through the medium of the main shaft F, driven by any suitable power.

The pan R has an inwardly-projecting rim, w, provided with a depending flange, x, and at about half-way of its depth this pan is provided with a trough, z, extending from the inner circumference toward the center, to leave a central opening, through which access may be had to the inner bottom portion of said pan. The trough z has a depending flange, z', and adapted to close the central opening formed by said trough and its flange is a perforated cover, Z, conical in shape and provided with a vertical collar, b', adapted to be removably secured to the shaft S by set-screws c', or other suitable means, said set-screws also serving to support the hopper r in operative position.

In the operation of my invention, motion being imparted to the various parts of the machine through the medium of the main shaft F, the quartz or other substance is fed from the vibrating hopper N to the crushing-rolls C, and from thence to the vibrating sieves O, where the coarser metallic particles are separated and retained, the residue passing on down to the trough P, from whence it is conducted to the hopper r and into the pan R, between the collar b' of the perforated conical cover Z and the hollow shaft S. Water from the supply-pipe T is introduced into the lower portion of the pan through the perforations in the lower hollow part of the shaft S, and said pan being revolved at a high rate of speed, the residue or tailings therein are thoroughly washed. By this washing of the residue or tailings the heavier portions or metals that may have escaped through the sieves are freed from the surrounding substances, and, being of greater specific gravity, tend to remain in the lower portion of the pan, while the lighter material overflows with the water through the perforated cover Z into the trough z. By centrifugal force

the heavier portions or metals remaining in the lower portion of the pan accumulate around the inner circumference and are prevented from rising by the downwardly-projecting flange z' of the trough z. Such particles as may have escaped through the perforated cover with the overflow from the pan-bottom are subjected to a further agitation in the trough z, and by centrifugal force the heavier portion or metals contained therein accumulate and remain between the inner upper wall of the pan and the flange x, depending from the rim w, the lighter and worthless material being carried entirely out of the pan by the overflow.

Having thus fully described my invention, what I claim as new, and desire to secure by Letters Patent, is—

1. A pan having an inwardly-projecting rim provided with a depending flange, an internal trough, also provided with a depending flange, a perforated cover, and a hollow revolving shaft provided with perforations, substantially as and for the purpose set forth.

2. A pan having an inwardly-projecting rim provided with a depending flange, an internal trough, also provided with a depending flange, a perforated conical cover having a vertical collar, the set-screws for securing the same, a hopper designed to fit upon said collar, and a hollow revolving shaft provided with perforations, substantially as and for the purpose set forth.

3. A pan having an inwardly-projecting rim provided with a depending flange, an internal trough, also provided with a depending flange, a perforated cover, and a hollow revolving shaft provided with perforations, in combination with a water-supply pipe inserted in the bore of said shaft, substantially as and for the purpose set forth.

In testimony that I claim the foregoing, I have hereunto set my hand, at Milwaukee, in the county of Milwaukee and State of Wisconsin, in the presence of two witnesses.

JOHN E. PARAMORE.
